UNITED STATES PATENT OFFICE

146,116

DESIGN FOR A LAMP

William Fred Masterson, Decatur, Ill., assignor to Faries Manufacturing Company, Decatur, Ill.,
a corporation of Illinois

Application November 15, 1945, Serial No. 123,776

Term of patent 14 years

(Cl. D48—20)

To all whom it may concern:

Be it known that I, William F. Masterson, a citizen of the United States, residing at Decatur, in the county of Macon and State of Illinois, have invented a new, original, and ornamental Design for a Lamp, of which the following is a specification, reference being had to the accompanying drawing, forming part thereof, in which—

Fig. 1 is a front elevation of a lamp showing my new design;

Fig. 2 is a side elevation;

Fig. 3 is a rear elevation;

Fig. 4 is a section taken on the line 4—4 in Fig. 3; and

Fig. 5 is a top or plan view.

The characteristic feature of my invention resides in the specific standard and supporting arm in association with the lamp and base as shown.

I claim:

The ornamental design for a lamp, substantially as shown and described.

WILLIAM FRED MASTERSON.
